S. S. GOLDMAN.

TROLLEY WIRE CROSSING, SWITCH, AND THE LIKE.

APPLICATION FILED APR. 24, 1912.

1,075,032.

Patented Oct. 7, 1913.

UNITED STATES PATENT OFFICE.

SAMUEL S. GOLDMAN, OF ST. LOUIS, MISSOURI.

TROLLEY-WIRE CROSSING, SWITCH, AND THE LIKE.

1,075,032.

Specification of Letters Patent.

Patented Oct. 7, 1913.

Application filed April 24, 1912. Serial No. 692,883.

To all whom it may concern:

Be it known that I, SAMUEL S. GOLDMAN, a citizen of the United States, residing at the city of St. Louis, State of Missouri, have invented certain new and useful Improvements in Trolley-Wire Crossings, Switches, and the like, of which the following is a specification, reference being had to the accompanying drawings, forming a part hereof.

This invention relates generally to trolley-wire crossings, switches, and the like, and more particularly to a certain new and useful trolley-wire crossing and trolley-wire switch or frog adapted and designed particularly for use in connection with the trolley shown and described in Letters Patent No. 931,292, granted to me August 17, 1909.

The trolley shown and described in said Letters Patent is designed and adapted to continuously operatively engage with a trolley-wire and not become accidentally separated or disengaged therefrom; and I have found that the trolley-crossings and switches or frogs now generally in use are not only not well adapted for use with my said trolley, but are all with more or less difficulty operatively connected to the intersecting or crossing trolley-wires and easily become broken or otherwise damaged.

The objects of my present invention are to provide a trolley-crossing, switch and the like which may not only be quickly and easily operatively and firmly engaged with the intersecting or crossing trolley-wires, but which is also simple in construction, cheap and economical to manufacture, and efficient and durable, and which is especially adapted and designed for use in connection with the trolley shown and described in said Letters Patent No. 931,292, and to improve generally upon articles or devices of the kind stated.

With these objects in view, my invention resides broadly in the novel form and construction of the several parts of my new trolley-crossing and switch and in the novel arrangement and combination of the same, all as will hereinafter be described and afterward pointed out in the claims.

In the drawings—Figure 1 is a side elevational view, partly in section, of a trolley-crossing embodying my invention; Fig.

2 is a plan view of the under or trolley-engaging face thereof; Fig. 3 is a detail fragmentary view of the upper face of one of the cross-members of my new trolley-crossing; Fig. 4 is a plan view of the under face of a trolley-switch or frog embodying my invention; and Fig. 5 is a sectional view on the line 5—5, Fig. 1.

In the accompanying drawings, for the purpose of illustrating and bringing out clearly the operative connection or engagement between the trolley of said Letters Patent and my new crossing and frog, I have in Fig. 1 shown in dotted lines a portion of the said trolley, said trolley comprising, as in said Letters Patent fully described, a trolley-wheel 1 rotatably mounted and arranged between side arms 2, and guard-wheels 3 provided on their upper surface with conical faces, as at 3^a, and on their lower surface with grooves of quarter-circle shape in cross-section, as at 3^b, providing bearing faces which normally overhang the groove in trolley-wheel 1.

A indicates the body portion of my new trolley-crossing, which may be of any suitable preferably metallic material. This body portion A, as shown particularly in Fig. 2, is substantially in the form of a cross and comprises similar members or trolley-tracks 4 and 5 substantially V-shaped in cross section and having flat oblique side faces intersecting or crossing at a point, as at 6, between their lengths and having their apices presented downwardly. At said point of crossing or intersection 6, each of said members or tracks 4 and 5 is interrupted or broken by a pair of transverse substantially V-shaped grooves, the angle of incline and the width of the flat faces of each of said grooves being the same as the angle of incline and the width of the flat oblique side faces or surfaces of said members 4 and 5, and, as shown particularly in Fig. 2, all of said grooves meeting at a central point or apex, as at 7, common to, and in alignment with, and on the same horizontal plane as, the apices of, said members or tracks 4 and 5.

With reference to said central point or apex 7, I have designated the near oblique faces of the grooves of the member 4 as 4' and the far faces thereof as 4'', and the near faces of the grooves of member 5 as 5' and the far faces thereof 5''. Thus, as will be

seen, the under surface of said point of crossing or intersection 6 of said members or tracks 4 and 5 is substantially in the form of a pyramid and central like flat oblique faces are provided in each of said members or tracks in alinement with the flat oblique side faces of the other, respectively, the near faces 4' of the grooves of member 4 being thus, as it might be said, continuations of the oblique side faces of member 5 and the near faces 5' of the grooves of member 5 being similarly continuations of the oblique side faces of member 4. Thus a practically continuous and uninterrupted path is provided for said guard-wheels 3 when traveling in either direction, the said guard-wheels 3 being adapted when traveling in one direction, as, for instance, on track 4, to pass freely and smoothly along and across member 5, and likewise when traveling on member 5 in the other direction, to similarly pass freely and smoothly along and across member 4, as will be obvious. It will, of course, be understood that guard-wheels 3 and the grooves of members 4 and 5 are of such relative dimensions that said guard-wheels 3, as shown in Fig. 1, will fit within said grooves, and that the material of sleeves 8 hereinafter described is comparatively thin, so as not to materially increase the diameter of the trolley-wire ends and retardingly engage with and prevent the easy and free travel therealong of said guard-wheels 3.

In mounting or supporting my new trolley-crossing in position, the crossing trolley wires are suitably cut at their point of intersection to provide four trolley-wire ends, said trolley-wire ends being received in suitable sleeves 8 mounted on said members 4 and 5 at the apices thereof, as shown clearly in Fig. 2, these sleeves 8 being preferably closed at their inner ends and extending slightly beyond the outer ends of said members. As the manner of, and means for, securing said trolley-wire ends in their respective sleeves is similar, the manner of and means for securing one of said trolley ends α in its sleeve 8^a on member 5 will be only here described, such description being applicable to all said sleeves and trolley-wire ends. At its apex, member or track 5 is longitudinally provided with an elongated slot, as at 9, communicating with the interior of said sleeve. On its upper or reverse face and within the groove thereof and opposite or above said sleeve 8^a, said member 5 is provided adjacent its end with a preferably cylindrical portion, or wedge-housing, as I will call it, 10 provided with a vertically-widened slot, as at 11, extending therethrough and in alinement with said slot 9. Fitting within said slot 9 and partly within said slot 11 and adapted to engage with said trolley-wire end α is a preferably elongated

rectangular block 12, provided on its lower edge with serrations or teeth, as at 12^a, adapted to impingingly engage with said trolley-wire end α ; and fitting in said slot 11 and forcibly interposed in said housing above said block 12 is a co-operating wedge-shaped block 13, whereby, as will be clear, block 12 will be held firmly and positively in engagement with said trolley-wire end α and said trolley-wire end α thereby securely but removably held within its sleeve 8^a. Thus, as will be seen, said trolley-wire ends will be firmly held in place and operatively together and, at the same time, my new crossing will be held in elevated position above the car-tracks, the trolley-wires being held elevated above the tracks by means of suitable cross-wires, not shown, as is well understood.

It will be further seen that my new crossing is comparatively simple in construction, may be cheaply and economically manufactured, is efficient and durable, and may be quickly and easily operatively arranged in position and connected to the crossing or intersecting trolley-wires, and it is to be understood that while, as has been stated, my new trolley-crossing is particularly adapted and designed for use in connection with the trolley shown and described in said Letters Patent, yet it might also be equally well used on a trolley-wire system having the cars equipped with other and different styles or constructions of trolley-wheels.

In Fig. 4, I have shown a trolley-switch or frog embodying my invention. In this form, the body portion thereof, B, which may likewise be of any suitable metallic material, comprises a straight substantially V-shaped member or trolley-track 14 having its apex presented downwardly and an intersecting like substantially V-shaped member or trolley-track 15 having its apex likewise presented downwardly, a strengthening web 16 being preferably provided between said tracks 15 adjacent the point of intersection therebetween. At the point of intersection between said tracks 14 and 15, track 14 is broken or interrupted by a groove having oblique faces, as shown, the right hand oblique face 14' thereof having an angle of incline substantially the same as the angle of incline of, and lying in the same oblique plane with, oblique faces 15^a of track 15 and the angle of incline of the left-hand oblique face 14'' of said groove being such as to permit guard-wheels 3 to freely pass from track 15 onto said track 14, or vice-versa, from track 14 onto track 15, as the case may be. At said point of intersection, said track 15 is obliquely cut away, as at 15', the angle of incline thereof being likewise such as to freely permit guard-wheels 3 to pass therealong when traveling on track 14. Thus, as will be seen, a practically continuous and

- uninterrupted track is provided for said guard-wheels 3 when traveling along track 15 and onto track 14 or vice-versa, as well as also a practically continuous and uninterrupted track for said guard-wheels when traveling along track 14. In my new frog, the intersecting trolley-wires are also suitably cut to provide three trolley-wire ends, and as these ends are received by and secured to body portion B in the same manner as the trolley-wire ends are received by and secured to body-portion A, further description thereof is here not deemed necessary. Body-portion B may, however, if desired, be also provided with suitable outwardly-extending eyes 17 for the attachment thereto of the usual street crossing wires. 10
- I am aware that minor changes in the form, arrangement, construction, and combination of the several parts of my new trolley-crossing and switch or frog, may be made and substituted for those herein shown and described without departing from the nature and principle of my invention.
- Having thus described my invention, what I claim and desire to secure by Letters Patent is:
1. A trolley-crossing or the like comprising a pair of intersecting trolley tracks substantially V-shaped in cross section, the apices of said tracks being presented downwardly and each of said tracks having opposite widened flat oblique side faces for directly receiving the oblique faces of a pair of substantially cone-shaped trolley wheels, and a substantially pyramidal portion at the point of intersection, and common to both of said tracks and having pairs of flat oblique faces lying in the same plane with, and forming continuations of, the flat oblique side faces of both said tracks, each of said tracks adjacent said pyramidal portion being provided with oppositely-disposed flat oblique faces extending outwardly directly from the base of the adjacent oblique faces of said pyramidal portion and forming therewith substantially V-shaped channels, substantially as and for the purposes stated. 20
  2. A trolley crossing or the like comprising a trolley track substantially V-shaped in cross section and having its apex presented downwardly, an elongated sleeve fixed to said track and extending parallel with and directly below the apex thereof, said sleeve being adapted to lengthwise removably receive therein a trolley wire end, and means adapted to engage said trolley wire end to removably secure the same in said sleeve; substantially as described. 30
  3. In a trolley crossing or the like, a body portion comprising a trolley track provided with a longitudinally extending elongated slot, an elongated sleeve fixed on the under side of said track and communicating with said slot, said sleeve being adapted to lengthwise removably receive therein a trolley wire end, a wedge-housing on the upper side of said trolley track and opposite to, and communicating through said slot with said sleeve, said wedge-housing being provided with a vertically widened slot in alinement with said first-mentioned slot, and wedge members adapted to fit in said slots and engage with said trolley wire end and said housing to removably secure the same in said sleeve; substantially as described. 40
  4. A trolley-crossing or the like comprising intersecting trolley-tracks substantially V-shaped in cross section, each of said tracks being provided at its apex at its outer ends with longitudinally-extending elongated slots, sleeves on the apex of each of said tracks communicating with said slots and adapted to receive trolley-wire ends, wedge-housings on the reverse side of said tracks and opposite said sleeves, and wedge-members adapted to fit in said slots and impingly engage with said trolley-wire ends and said housings; substantially as described. 50
  5. A trolley-crossing or the like comprising intersecting trolley-tracks substantially V-shaped in cross section, each of said tracks being provided at its apex at its outer ends with longitudinally-extending elongated slots, sleeves on the apex of each of said tracks communicating with said slots and adapted to receive trolley-wire ends, wedge-housings on the reverse side of said tracks and opposite said sleeves and provided with slots extending therethrough and in alinement with said track-slots, and wedge-members adapted to fit in said alining slots and impingly engage with said trolley-wire ends and said housings; substantially as described. 60
  6. A trolley-crossing or the like comprising intersecting trolley-tracks substantially V-shaped in cross section, each of said tracks being provided at its apex at its outer ends with longitudinally-extending elongated slots, sleeves on the apex of each of said tracks communicating with said slots and adapted to receive trolley-wire ends, wedge-housings on the reverse side of said tracks and opposite said sleeves and provided with slots extending therethrough and in alinement with said track-slots, and coöperating wedge-members adapted to fit in said alining slots and impingly engage with said trolley-wire ends and said housings; substantially as described. 70
  7. In a trolley-crossing, a body-portion comprising a member provided at its ends with longitudinally-extending elongated slots, sleeves on said member communicating with said slots, said sleeves being adapted to receive trolley-wire ends, wedge-housings on the reverse side of said member and opposite said sleeves, and wedge-members 80

adapted to fit in said slots and impingingly engage with said trolley-wire ends and said housings; substantially as described.

8. A trolley-crossing or the like comprising a body-portion having a trolley-track substantially V-shaped in cross-section provided at its apex and at its ends with longitudinally-extending elongated slots, sleeves on the apex of said track communicating with said slots and adapted to receive trolley-wire ends, wedge-housings on the reverse side of said track and opposite said sleeves, and wedge-members adapted to fit in said slots and impingingly engage with 10 said trolley-wire ends and said housings; substantially as described.

9. In a trolley-crossing or the like, a body-portion comprising intersecting members provided at their outer ends with longitudinally-extending elongated slots, sleeves on said members communicating with said slots, said sleeves being adapted to receive trolley-wire ends, wedge-housings on the reverse side of said members and opposite 20 said sleeves, and wedge-members adapted to 25 fit in said slots and impingingly engage with said trolley-wire ends and said housings; substantially as described.

fit in said slots and impingingly engage with said trolley-wire ends and said housings; substantially as described.

10. In a trolley-crossing or the like, a body-portion comprising intersecting members provided at their outer ends with longitudinally-extending elongated slots, sleeves on said members communicating with said slots, said sleeves being adapted to receive trolley-wire ends, wedge-housings on the reverse side of said members and opposite said sleeves and provided with slots extending therethrough and in alignment with said first-mentioned slots, and coöperating wedge-members adapted to fit in said aligning slots and impingingly engage with said trolley-wire ends and said housings; substantially as described.

In testimony whereof, I have signed my name to this specification, in the presence of 45 two subscribing witnesses.

SAMUEL S. GOLDMAN.
